CLAIM

The ornamental design for a dispensing container, as shown and described.

DESCRIPTION

FIG. 1 is a top, front, right perspective view of a first embodiment of a dispensing container in accordance with the new design.

FIG. 2 is a front elevational view of the first embodiment of the dispensing container.

FIG. 3 is a back elevational view of the first embodiment of the dispensing container.

FIG. 4 is a left side elevational view of the first embodiment of the dispensing container.

FIG. 5 is a right side elevational view of the first embodiment of the dispensing container.

FIG. 6 is a top view of the first embodiment of the dispensing container.

FIG. 7 is a bottom view of the first embodiment of the dispensing container.

FIG. 8 is a top, back, left perspective view of the first embodiment of the dispensing container with the bail in an extended position.

FIG. 9 is a top, back, left perspective view of the first embodiment of the dispensing container with the bail in a locked position.

FIG. 10 is a top, front, right perspective view of a second embodiment of a dispensing container in accordance with the new design.

FIG. 11 is a front elevational view of the second embodiment of the dispensing container.

FIG. 12 is a back elevational view of the second embodiment of the dispensing container.

FIG. 13 is a left side elevational view of the second embodiment of the dispensing container.

FIG. 14 is a right side elevational view of the second embodiment of the dispensing container.

FIG. 15 is a top view of the second embodiment of the dispensing container.

FIG. 16 is a bottom view of the second embodiment of the dispensing container.

FIG. 17 is a top, back, left perspective view of the second embodiment of the dispensing container with the bail in an extended position.

FIG. 18 is a top, back, left perspective view of the second embodiment of the dispensing container with the bail in a locked position.

FIG. 19 is a top, front, right perspective view of a third embodiment of a dispensing container in accordance with the new design.

FIG. 20 is a front elevational view of the third embodiment of the dispensing container.

FIG. 21 is a back elevational view of the third embodiment of the dispensing container.

FIG. 22 is a left side elevational view of the third embodiment of the dispensing container.

FIG. 23 is a right side elevational view of the third embodiment of the dispensing container.

FIG. 24 is a top view of the third embodiment of the dispensing container.

FIG. 25 is a bottom view of the third embodiment of the dispensing container.

FIG. 26 is a top, back, left perspective view of the third embodiment of the dispensing container with the bail in an extended position.

FIG. 27 is a top, back, left perspective view of the third embodiment of the dispensing container with the bail in a locked position.

FIG. 28 is a top, front, right perspective view of a fourth embodiment of a dispensing container in accordance with the new design.

FIG. 29 is a front elevational view of the fourth embodiment of the dispensing container.

FIG. 30 is a back elevational view of the fourth embodiment of the dispensing container.

FIG. 31 is a left side elevational view of the fourth embodiment of the dispensing container.

FIG. 32 is a right side elevational view of the fourth embodiment of the dispensing container.

FIG. 33 is a top view of the fourth embodiment of the dispensing container.

FIG. 34 is a bottom view of the fourth embodiment of the dispensing container.

FIG. 35 is a top, back, left perspective view of the fourth embodiment of the dispensing container with the bail in an extended position; and,

FIG. 36 is a top, back, left perspective view of the fourth embodiment of the dispensing container with the bail in a locked position.

The remaining broken lines, shown in the drawings, represent portions of the dispensing container which form no part of the claimed design.
